UNITED STATES PATENT OFFICE.

WILLIAM HYDE ROBERTS, OF PHILADELPHIA, PENNSYLVANIA, ASSIGNOR
TO GEORGE W. ENNIS & CO., OF SAME PLACE.

DESIGN FOR A CURTAIN FABRIC.

SPECIFICATION forming part of Design No. 15,919, dated March 3, 1885.

Application filed January 23, 1885. Term of patent 3½ years.

To all whom it may concern:

Be known that I, WILLIAM HYDE ROBERTS, a subject of the Queen of Great Britain, residing at Philadelphia, in the county of Philadelphia and State of Pennsylvania, have invented and produced a new and original Design for a Curtain Fabric; and I do hereby declare that the photographic print accompanying this specification conveys to any one skilled in the art a clear understanding of the same, and is sufficient to enable such person to use my invention.

The leading features of my design consist—

First. In the representation at A of ornamental scrolls, leaves, and flowers, ornamental cross-guard B, and ornamental cross and side borders CCC. These parts combined repre-

sent the ornamental design of a dado for a curtain fabric, as shown.

Second. In the representation at D and E of bunches of flowers arranged, as shown, on a figured ground, with the ornamental side borders CC. These parts combined represent the body of the curtain fabric, as shown, (only part of the body being shown in the print.)

I claim as my invention and desire to secure by Letters Patent—

The design for a curtain fabric, as shown and described.

WILLIAM HYDE ROBERTS.
